UNITED STATES PATENT OFFICE.

GEORGE L. CLOSE, OF MOUNT VERNON, NEW YORK, ASSIGNOR TO CHURCH, WEBB & CLOSE, INC., OF NEW YORK, N. Y., A CORPORATION OF NEW YORK.

HEAD-GEAR.

1,284,240.

Specification of Letters Patent. Patented Nov. 12, 1918.

Application filed December 29, 1917. Serial No. 209,468.

To all whom it may concern:

Be it known that I, GEORGE L. CLOSE, a citizen of the United States, and resident of Mount Vernon, in the county of Westchester and State of New York, have invented certain new and useful Improvements in Head-Gear, of which the following is a specification.

This invention relates more particularly to head gear designed for the use of aviators; and the principal object of the invention is to provide a helmet or hood with a cape extension so that the head and neck and a part of the shoulders of the wearer will be protected, the cape being divided from the face opening of the hood to the lower margin of the cape and provided with means for readily closing it and locking it closed.

Another object of the invention is to provide the head-gear with a flexible, waterproof, non-absorbent exterior and a soft, fleecy interior.

There are other objects and advantages of the invention which will appear hereinafter, resulting from the detailed construction and design of the head-gear.

In the drawings, Figure 1 is a perspective view of the head-gear open and in condition to be applied;

Fig. 2 a face view of the helmet as it is when applied;

Fig. 3 a horizontal sectional view on the line III—III of Fig. 1;

Fig. 4 a similar view showing the flap which is designed to cover the ear opening, rolled up and secured in its rolled condition;

Fig. 5 a detail enlarged view of the sliding means for interlocking the margins of the divided portion of the cape;

Fig. 6 an enlarged detail view of one of the interlocking metal studs of the closure device; and

Fig. 7 a detail perspective view of the slide adapted to bring into interlocking engagement the studs of the closure means.

Referring to the various parts by numerals, 1 designates the helmet or hood which is formed with the face opening 2; and from the lower end of the helmet the shoulder cape 3 extends. The lower edge of the cape

is continuous and unbroken, the marginal seam 4 extending entirely around the said lower edge. The cape is divided vertically as at 5 from the chin portion of the face opening to the marginal seat 4, said seam being reinforced across the opening by a strip 6 which bridges the opening at the said seam 4. The marginal edges of the opening 5 are provided with oppositely arranged interlocking metal studs 7, shown clearly in Fig. 5, each marginal edge of said opening being provided with a series of such studs which are in staggered relation, the studs on one margin of the said opening being adapted to engage corresponding studs on the opposite margin thereof. These metal studs, as shown in Fig. 5, are provided on their upper surfaces with projections and on their under surfaces with sockets, said sockets being adapted to receive the projections of the adjoining engaging studs of the opposite margin. These studs are brought into interlocking engagement by means of a Y-shaped hollow slide 8. To bring the two sets of studs into interlocking engagement the slide is drawn upwardly to the chin opening. When the studs are interlocked the two margins of the opening 5 are closely connected, the connection resembling metal stitching and securing a very tight closure. This closure means is an article of commerce and forms no part of my invention except in its application. To close the opening 5 it is merely necessary to draw the slide 8 upwardly to the margin of the face opening. The separate the margins of the openings it is only necessary to pull the said margins outwardly away from each other, beginning at the upper ends thereof, the slide being moved downwardly to the reinforcing piece 6 by the outward motion of the cape sections. Secured to the inner side of the cape along one of the margins of the opening 5, is a bridge piece 9, said bridge piece extending for a considerable distance across the opening 5 and serving as a windbreak. The upper end of this bridge piece is extended above the lower margin of the face opening 2 and is lined on its inner side with fleecy material 10. This upper end of the bridge piece is pro-

vided with members 11 of two snap fasteners, the coöperating members 12 of said snap fasteners being secured to the cape portion on opposite sides of the opening 5 as shown 5 clearly in Fig. 1. When the slide 8 has been moved upwardly to close the opening 5 the upper end of the bridge piece is turned outwardly and downwardly to bring the members 11 of the snap fasteners into en- 10 gagement with the members 12 thereof to thereby lock the upper margins of the opening 5 together and to prevent the separation of said margins by any outward pull on the cape sections. The outwardly turned 15 or folded end of the bridge piece covers the slide 8 and prevents it contacting with the chin of the wearer. It is manifest that that portion of the bridge piece which is within the cape bridges the joint between the mar- 20 gins of the opening 5 and effectually prevents the inward passage of wind. The sections of the cape cannot be separated without first releasing the overlapping and locking portion of the bridge piece. To open 25 the cape it is necessary to first release the locking portion of the bridge and to then pull outwardly the upper ends of the marginal portions of the opening 5. This pro- 30 vides for a very ready removal of the head- gear from the wearer. It is well known that aviators become very cold in high altitudes and it is very desirable that their head-gear be so designed that it may be readily and quickly removed even though the hands of 35 the wearer are very cold and stiff.

The helmet or hood 1, at points which are approximately opposite the ears of the wearer, are provided with apertures 13 shown in dotted lines in Fig. 1 and shown 40 clearly in Figs. 3 and 4. Secured to the exterior of the hood are flexible flaps 14, said flaps on their inner sides carrying members 15 of snap fasteners, the other members 16 thereof being secured to the hood in such 45 position as to be engaged by the members 15 when the flaps 14 are extended and overlie the openings 13. This is the position of the flaps when the hood is in use and it is desired to cover the openings 13 to prevent 50 wind entering them. The flaps 14 on their exterior carry members 17 of snap fasteners, the other members 18 thereof being connected to the hood close to the point of connection between the flap 14 and the hood. 55 When the flaps 14 are not extended over the ear openings they are rolled up and the members 17 are snapped into the coöperating members 18 in order to secure the flaps to the side of the hood in the form of a roll 60 19, as indicated in Fig. 4, thereby leaving the ear openings free for the purpose of ventilation and also to enable the wearer to hear readily.

65 Detachably secured to the lower end of the hood, by means of a snap fastener 20, is a chin-protecting strap 21, said strap being lined on its inner side with suitable fleecy material, said material being carried around on the outer face of the chin strap as clearly 70 illustrated in the drawing. Connected to 75 one end of the said chin strap is a strap 22 on which is mounted a slide 23 which carries one member 24 of a snap fastener, the other member thereof being secured to the hood in a position directly opposite the fastener 20. 75 By means of the slide 23 and the strap 22 the chin strap may be lengthened or shortened in order to fit the wearer. It is manifest that by reason of the use of the snap fastener 20 the chin strap may be entirely 80 detached from the hood if desired. In removing the head-gear from the wearer it is only necessary to detach one end of the chin strap, as indicated in Fig. 1.

85 The exterior of the hood and cape is preferably of a soft, flexible, non-absorbent, waterproof material in order that it will dry quickly and also prevent the inner fleecy lining from absorbing moisture from the exterior covering. I prefer to use a soft, 90 woven, rubberized fabric of suitable thickness and strength.

95 The exterior of the cape and hood is formed of sections of material which extend from the top of the hood to the lower margin of the cape so that the exterior seams are all vertical, thereby facilitating the downward discharge of moisture which may collect thereon and preventing said moisture 100 lodging in the seams and seeping through into the fleecy inner lining. The exterior of the hood and cape is preferably formed of four sections,—two side sections 25 and a rear section 26, all of which extend from the top of the hood to the lower margin 4 of the cape; and a front section 27 which extends from the crown of the cape to the upper margin of the face opening. It is to be noted that all of the seams connecting 105 these sections are substantially vertical. 110

115 It is well known that aviators have great difficulty in retaining their helmets when traveling at high speed, due to the wind pressure. It is obvious that with an integral cape which is adapted to be placed under the coat, the helmet or hood is effectually secured in position and cannot be torn off by the high winds. It is also obvious that the locking piece bridging the joint between the two cape sections and preventing the release of the locking device 120 will also be effective in preventing the cape being opened by the high winds.

125 What I claim is:

1. A hood comprising a crown portion and a cape portion connected by an inter-

mediate contracted portion, said hood being formed with a face opening and having the cape portion thereof divided from the lower edge of the face opening to a point 5 adjacent the lower margin of the cape portion to form a slit to permit expansion of the contracted portion of the hood, interlocking closure devices held to the cape portion at opposite sides of the slit adapted to 10 be separated by pulling sidewise on the edges of the face opening, and means for detachably locking the sections of the divided cape portion together adjacent the upper end of the slit to prevent relative movement of the interlocking closure devices.

2. A hood formed with a face opening and a cape portion divided from the lower edge of the face opening to a point adjacent the lower margin of the cape, interlocking closure devices secured to the edges of the sections of the divided cape portion, means 20 shiftably held to the cape portion for moving said closure devices into interlocked relation, and means for locking the sections of 25 the divided cape portion together adjacent the lower edge of the face opening to prevent accidental separation of the interlocked closure devices.

3. A head-gear for aviators and the like 30 comprising a hood, a cape at the lower end of said hood, said hood being formed with a face opening and the cape being divided from the margin of said face opening to the lower margin of the cape and the lower margin 35 of the cape being continuous, interlocking closure devices secured to the margins of the opening in the cape, a sliding means for bringing said devices into interlocking engagement, and means for locking together 40 the upper ends of the cape sections at the face opening, said locking means covering the slide of the closure means.

4. A head-gear for aviators and the like 45 comprising a hood, a cape at the lower end of said hood, said hood being formed with a face opening and the cape being divided from the margin of said face opening to the lower margin of the cape and the lower margin 50 of the cape being continuous, interlocking closure devices secured to the margins of the opening in the cape, a sliding means for bringing said devices into interlocking engagement, a bridge piece secured along the inner surface of one margin of the 55 cape opening and extending across said opening, the upper end of said bridge piece being adapted to be turned outwardly and downwardly, and snap fasteners carried by the end of said bridge piece and by the cape 60 sections whereby said bridge piece may be secured to the cape sections to lock the upper ends of said sections together and inclose the slide of the closure means.

5. A head-gear for aviators and the like comprising a hood, a cape at the lower end 65 of said hood, said hood being formed with a face opening and the cape being divided from the margin of said face opening to the lower margin of the cape and the lower margin 70 of the cape being continuous, interlocking closure devices secured to the margins of the opening in the cape, a sliding means for bringing said devices into interlocking engagement, a bridge piece secured along the inner surface of one margin of the cape 75 opening and extending across said opening, the upper end of said bridge piece being adapted to be turned outwardly and downwardly, snap fasteners carried by the end 80 of said bridge piece and by the cape sections whereby said bridge piece may be secured to the cape sections to lock the upper ends of said sections together and inclose the slide of the closure means, a chin strap, and means for detachably securing one end of said chin 85 strap in position across the lower end of the face opening.

6. A hood formed with a face opening and a divided cape portion, interlocking devices held to the cape portion at opposite 90 sides of the division line for separably connecting the edges of the cape portion together, a bridge piece adapted to cover the joint between the separably connected edges of the cape, and means whereby said bridge 95 piece may be detachably secured to the cape portion at opposite sides of the division line to prevent separation of the interlocking devices.

7. A hood formed with a face opening and a divided cape portion, interlocking devices held to the cape portion at opposite sides of the division line for separably connecting the edges of the cape portion together, a bridge piece adapted to cover the joint between the separably connected edges of the cape, means whereby said bridge piece may be detachably secured to the cape portion at opposite sides of the division line to prevent 105 separation of the interlocking devices, a chin 110 protecting strap adapted to extend across the lower portion of the face opening, and means for detachably securing the ends of the chin strap to the hood at opposite sides 115 of the face opening.

8. A hood comprising a crown portion and a cape portion connected by an intermediate contracted portion, said hood being formed with a face opening and having the cape portion thereof divided from the lower edge of the face opening to a point adjacent the lower margin of the cape portion to form a slit to permit expansion of the contracted portion of the hood, interlocking closure devices held to the cape portion 120 at opposite sides of the slit adapted to be 125

separated by pulling sidewise on the edges of the face opening, a bridge piece held to the cape portion adapted to cover the joint between the separably connected edges of 5 the divided cape portion and formed with an extension at its upper end adapted to be folded over the lower edge of the face open-

ing, and means for detachably securing the folded end of said bridge piece to the cape portion at opposite sides of the slit. 10

In testimony whereof I hereunto affix my signature.

GEORGE L. CLOSE.
